UNITED STATES PATENT OFFICE.

JOHN O. GARGAN, OF BROOKLYN, NEW YORK, ASSIGNOR TO WESTERN ELECTRIC COMPANY, INCORPORATED, OF NEW YORK, N. Y., A CORPORATION OF NEW YORK.

VACUUM-TUBE SOCKET.

Application filed September 5, 1918. Serial No. 252,721.

To all whom it may concern:

Be it known that I, JOHN O. GARGAN, a citizen of the United States, residing at Brooklyn, in the county of Kings and State 5 of New York, have invented certain new and useful Improvements in Vacuum-Tube Sockets, of which the following is a full, clear, concise, and exact description.

This invention relates to socket structures, 10 and has for its object the provision of a socket in which spare vacuum tubes used in telegraph sets may be carried without undue vibration or liability to breakage.

In telegraph sending and receiving sets, 15 particularly of the portable type, adapted to be used in field work, it is often advisable to carry spare tubes. Due to the rough usage to which these sets are often subject, it is necessary to provide a holder for them, 20 of such construction that the tube shall not readily fall out.

The invention comprises a socket into 25 which the tube is inserted and to which it is locked by a bayonet slot construction acting in combination with a resilient means at the base of the socket which operates on the base of the tube to hold it in place.

The invention is illustrated in the drawing of which Fig. 1 is an elevation of the 30 tube and socket with a portion of the base broken away, and showing the device attached to a portion of a portable telegraph set, and Fig. 2 is a plan view looking downward upon the device with the tube removed from the socket.

As shown in the drawing, the socket is 35 adapted to be attached to a suitable portion, preferably the inside of the cover 1 of a portable telegraph set, and is mounted on a base 2 which is fastened in any suitable manner to the cover 1. This base comprises a somewhat U-shaped member, having at each end offset portions 3 which extend in a direction parallel to the surface 40 of the cover to which it is attached. Two rather thick strips of rubber 4, or other suitable resilient material, extend across the U-shaped depression in the base 2, from one portion 3 to the other portion 3 at opposite 45 ends of said portions 3. These rubber strips are, at each end, fastened to the portions 3 of base 2 by means of suitable screws 5. A vacuum tube socket 6 is supported from the rubber strips 4 by means of a plate 7 50 permanently connected to the socket and

forming a part of the bottom wall thereof, which plate is attached to the rubber strips by means of the screws 8. In the bottom wall of the socket 6 and the plate 7 are a plurality of aligned apertures 9 through 60 which are adapted to extend the electrodes 10 of a vacuum tube inserted in the socket. A stud 11 is rigidly mounted in the center of plate 7 of the bottom wall of the socket and centrally with respect to said apertures 65 9 and extends downwardly from the bottom of the socket into the U-shaped portion of bracket 2. A disk 12 is positioned against the bottom of plate 7, and has an aperture therein surrounding stud 11. This disk is 70 of such diameter as to substantially cover the apertures 9 in the bottom wall of the socket and is normally held against the bottom of plate 7 by means of a spring 13 which extends between disk 12 and a washer 18, 75 held on to stud 11 by a pin 14 at the outer end of stud 11.

The device which is shown in the form of a vacuum tube of any suitable construction is preferably provided with a base portion 80 15 having at its lower end a plurality of electrodes 10 which are so arranged that, when the tube is inserted in the socket 6, the electrodes will extend through the apertures. A slot 16 is provided in the side of 85 socket 6 which is adapted to cooperate with a pin 17 on the plug of the tube or lamp to form a bayonet lock.

In the operation of the device, a tube is 90 inserted in the socket 6, the pin 17 entering slot 16, and the electrodes 10 entering apertures 9. As the tube is thrust into the socket sufficiently far to permit it to be turned so that pin 17 will enter the side portion of slot 16, the electrodes contacting 95 with disk 12 will depress the same against the action of spring 13. The compression of spring 13 will thereafter tend to maintain the bayonet lock effective so that the tube will have no tendency to fall out. A 100 provision of the resilient portions 4, on which the socket and tube are mounted, prevents any vibrations or jars contributed to the casing to which the bracket 2 is attached, from seriously affecting the lamp. 105

It is well within the spirit of my invention to provide such a structure as would accommodate a plurality of such tubes; for instance, the plate 7 might be extended in length to form a part of the bottom wall of 110

more than one socket; the ends of the plate in that case would similarly rest on resilient members attached to a bracket. The only change necessary to be made would be in 5 the size of the parts used.

What is claimed is:

1. A holder for vacuum tubes comprising a base, a cup shaped socket attached to said base and having a bayonet slot in its side, 10 the bottom of said socket having a plurality of apertures therein, a stud secured to and beneath said bottom, a disk slidable on said stud and of such diameter as to substantially cover said apertures, a washer held 15 on the end of said shaft, and a spring around said shaft in compression between said washer and disk.
2. A holder for vacuum tubes comprising a base having a pin extending from its 20 side and a plurality of electrodes extending from its bottom, a cup shaped socket for said base having a bayonet slot adapted to receive said pin, the bottom of said socket having a plurality of apertures adapted to 25 receive said electrodes, a stud extending centrally beneath and away from said bottom, a disk slidable on said stud and adapted to bear against the bottom of the socket and substantially cover said apertures, and a 30 spring on said stud and bearing against said disk to hold it normally in position to cover said apertures.

3. The combination with a base having a plurality of projecting electrodes, of a socket having apertures adapted to receive 35 said electrodes, a locking connection between socket and base, and a member yieldably urged against a plurality of said electrodes for maintaining said locking connection.

4. A holder for vacuum tubes comprising 40 a base, a cup shaped socket mounted thereon, said socket being adapted to embrace the base of a vacuum tube, and spring-pressed means mounted on said socket for retaining a vacuum tube in said socket. 45

5. A holder for vacuum tubes comprising a base, a cup shaped socket mounted thereon, said socket being adapted to embrace the base of a vacuum tube and having an 50 aperture in its bottom wall to receive an electrode of a vacuum tube, and spring-pressed means mounted on said socket and adapted to contact with said electrode for holding said vacuum tube in said socket.

6. A holder for vacuum tubes comprising 55 a base, a socket mounted thereon having apertures adapted to receive a plurality of electrode terminals, a stud mounted on said socket, and spring means on said stud adapted to contact with said electrodes. 60

In witness whereof, I hereunto subscribe my name this 29th day of August A. D. 1918.

JOHN O. GARGAN.
